UNITED STATES PATENT OFFICE.

ALLEN I. BLANCHARD, OF CHICAGO, ILLINOIS.

RAILROAD-TICKET.

SPECIFICATION forming part of Letters Patent No. 568,399, dated September 29, 1896.

Application filed May 8, 1893. Serial No. 473,346. (No model.)

To all whom it may concern:

Be it known that I, ALLEN I. BLANCHARD, a citizen of the United States, residing at Chicago, in the county of Cook and State of Illinois, have invented a certain new and useful Improvement in Railroad-Tickets, of which the following is a description, reference being had to the accompanying drawings, forming part of this specification.

10 My invention relates to that class of tickets which are formed from blanks having the names of a series of stations printed in duplicate upon them in two parallel adjacent columns, and which are adapted to be so torn in two or otherwise separated longitudinally of said columns as to form a stub and a ticket portion proper, each portion having upon it in whole or in part one of the columns of names and having the name of the 15 destination station indicated by a notch or projection on the margin of the ticket opposite such name. The name of the starting station or station from which the ticket is sold is written or printed upon the body of the ticket, so that when the ticket is issued 20 it reads from such station to the particular station indicated by the notch or projection on the margin of the ticket. The separation of the ticket-blank into stub portion and ticket portion proper, with the destination station indicated upon each in the above manner, has generally been effected by tearing the blank in two against a ruler or tearing-blade having a lateral projection which 25 forms a notch in the margin of one portion of the ticket and a corresponding projection upon the other portion. By placing the ticket-blank beneath the ruler or tearing-blade in such position that the projection 30 upon the latter will overlie the name of the station to which the ticket is to read (the destination station) and then tearing the ticket in two along the edge of the ruler a projection is formed upon the edge of one 35 portion of the ticket opposite such name and a notch upon the other portion of the ticket opposite the duplicate name upon the latter.

40 It has been found that where the blank is divided upon a single straight line between the two columns of names, interrupted simply by the point or projection opposite the destination station, the ticket is not suffi-

ciently protected, either against accidental mutilation or fraudulent manipulation. The projection upon the one portion of the ticket 55 is liable to be accidentally torn off, or purposely removed, in which event it is not possible to tell to what station the ticket originally read. So, too, it has been found that the simple notch opposite the destination station upon the other portion of the ticket can be so filled up as to escape observation and a new notch be torn in the ticket opposite another station, so that dishonest agents may in this manner, and by collusion with the 60 train-conductors or otherwise, be enabled to defraud the company. In one form of tickets of this class an attempt has been made to overcome these objections by separating the ticket-blank upon two intersecting lines, instead of a single straight line, the two lines meeting each other at a very obtuse angle and the projection which indicates the destination station being formed at their junction, so that if the projection be torn off the original destination station may be determined by 65 prolonging the lines of the margin of the ticket to their point of intersection, which will be opposite the name of such station. In such tickets, owing to the separation of the stub portion 70 from the ticket portion proper upon the intersecting lines, the names of all the stations excepting the destination station are either partly or wholly removed from one portion of the ticket and left upon the other. This is 75 objectionable, for the reason, among others, that the names of the stations are generally printed upon the ticket in the regular order of the positions they occupy along the line of road, so that if the name of the destination station should accidentally be mutilated or purposely changed it may nevertheless be readily identified by the names of the stations adjacent to it in the column upon the ticket; but if the names of all the stations excepting the destination station be partly or wholly removed from one portion of the ticket, as in 80 the form of ticket above described, then the name of the destination station itself may be erased and the name of another station inserted without nearly so much risk of detection as where the names of the adjacent stations remain in regular order upon the ticket. For this and other reasons such 85

90

95

100

tickets fail to effectually prevent fraudulent manipulations.

It is the object of my invention to produce a ticket which will be free from objections to former ones and proof against fraudulent manipulation of any kind, and this I accomplish chiefly by my novel method of indicating the destination station, which consists in so separating the ticket-blank as to form upon the margin of one portion of the ticket, preferably upon the passenger's portion or ticket proper, two adjacent notches, one upon either side of the name of the destination station, with an intermediate projection opposite such name, and upon the margin of the other portion or stub two adjacent projections, one upon each side of the name of the destination station, with an intermediate notch between them opposite such name.

My invention also relates to the production of a round-trip or return ticket of the same character as the one-way ticket heretofore described; that is to say, a round-trip ticket in which the name of the destination station is indicated upon both the going portions and return portions of the ticket and upon the stub by notches or projections along the margins of said three portions opposite the name of the destination station; and in my improved ticket the notches and projections upon all three portions of the ticket are formed at the same time and by the same act, so that a round-trip ticket may be issued about as easily and quickly as a one-way ticket.

My invention also relates to other features of novelty tending to the prevention of fraudulent manipulation and to convenience in use, all as will be hereinafter set forth, and specifically pointed out in the claims.

In the accompanying drawings, Figure 1 shows the ticket-blank from which my new ticket is formed. Fig. 2 shows said blank separated into the stub portion and passenger's portion, the latter having the date-limitations punched in it and also being punched to indicate the checking of baggage. Fig. 3 shows the ruler or tearing-blade by means of which the blank of Fig. 1 is separated into the portions shown in Fig. 2. Fig. 4 shows a blank for a round-trip ticket, and Fig. 5 a round-trip ticket and stub formed from the blank of Fig. 4.

The same letters of reference indicate identical parts in all the figures.

The ticket-blank shown in Fig. 1 has the names of the stations to which the ticket may be made to read printed in two parallel columns, one upon the stub portion A and the other upon the passenger's portion B of the blank, and preferably separated by a heavy black line C. The numbers of the stations are also preferably printed upon the blank immediately in front of the names of the respective stations in one or both columns. At the lower ends of the columns of station-names are a series of names indicating the different classes for which the ticket may be

issued, such as "Clergy," "Half-fare," "Second-class," and so on. In addition to the columns of station-names and classes the stub portion of the ticket bears the usual printed matter, and also the words "From — to station opposite notch." The blank space in the line quoted is for the insertion of the name of the selling-station. This may be stamped or written in the blank space by the agent selling the ticket, but in the tickets for sale at the more important stations upon the line of road the name of the selling-station will be generally printed upon the ticket either at the same time the ticket is printed or at some other time before the supply of tickets is delivered to the ticket-agent for use. The passenger's portion B of the blank also bears the usual printed matter in addition to the column of station-names and classes and the words "From — to station indicated on tongue between notches in margin," the blank space being for the insertion of the name of the selling-station in the same manner as above.

The ruler or tearing-blade by which the blank shown in Fig. 1 is separated into the stub and passenger's portions shown in Fig. 2 is illustrated in Fig. 3, where it will be seen that one edge of the blade is provided with two laterally-projecting points D E with an intermediate notch F. Upon placing this blade over the blank shown in Fig. 1, with the right-hand edge of the blade between the two parallel columns of station-names and with the notch F embracing the first letter of the name of the desired destination station, and then pressing the blade tightly against the blank and bringing the portion B of the ticket firmly to vertical position against the edge of the blade, two notches will be torn in the portion B of the ticket at opposite sides of and immediately adjacent to the name of the destination station, and the latter name will remain immediately opposite and partly upon the projection formed by said notches. It is apparent that the projection thus formed is completely housed between the notches and lies within the marginal line of the coupon, and is therefore less liable to accidental mutilation. If no special class is to be indicated, as will generally be the case where the ticket is a first-class one, the passenger's portion B may now be completely severed from the stub portion A along the edge of the blade. If, however, the name of the class is to be indicated, the ticket-blank, after the portion B has been drawn to vertical position to indicate the destination station, will be torn in two along the edge of the blade from the upper edge of the ticket to a point below the name of the destination station, and the blank will then be slid along under the blade or the blade moved over the blank until the notch F in the blade is opposite the class to be indicated, whereupon the portion B of the blank will be again drawn to vertical position to tear notches in the blank upon oppo-

site sides of the name of the class, and the blank will then be completely severed against the edge of the blade to form the stub portion and passenger's portion shown in Fig. 2.

5 The notches and intermediate projection upon the margin of the passenger's portion of the ticket will leave counterpart projections and an intermediate notch upon the stub portion, and the name which stands opposite this 10 notch upon the stub portion will indicate the name of the station for which the ticket was sold.

As before stated, tickets of this class have heretofore been formed by tearing the blank 15 in two against a blade having a single projection, such as D or E, so that a single notch would be formed in one portion of the ticket and a single projection upon the other. As also explained before, the projection was liable 20 to be torn off the one portion of the ticket, and the notch could be skilfully filled up upon the other portion of the ticket, causing in the one case confusion and uncertainty, if nothing more, and in the other enabling the 25 ticket to be fraudulently manipulated.

From the foregoing description of my invention it will be seen that the name of the destination station upon the passenger's portion of the ticket is so thoroughly and permanently 30 indicated by the notches upon the opposite sides of it that alteration or fraudulent manipulation of this portion of the ticket is practically impossible. Even if the projection between the notches be torn off the name of the 35 destination station may still be determined by said notches, and the portion of the margin of the ticket torn away is so large that it is not practicable to replace it without detection even by skilful work. On the other hand, 40 the portion of the passenger's part of the ticket which is left adhering to the stub portion of the ticket, carrying the two projections with the intermediate notch, is so large that its removal and the attaching of a corresponding portion at some other point along the 45 margin of the stub is also practically impossible. It will therefore be seen that my novel method of separating the ticket upon a line which forms not only a projection opposite the destination station, as heretofore, 50 but also forms two deep notches upon each side of such name, produces both a stub and a ticket proper, which are not liable to accidental mutilation and which are not susceptible of fraudulent manipulation.

It will be understood that it is not essential to my present invention, any more than it has been essential in the tickets of this class heretofore in use, that there should be two duplicate series or columns of station-names, since a column containing simply the numbers of the stations may be printed upon the stub portion of the blank opposite the names of the corresponding stations upon the passenger's portion, the notch in the margin of the stub portion opposite a given number thereon serving to indicate the station for which the

ticket was sold; but it is preferable to provide two duplicate series of station-names, and also to number the stations in one or both 70 columns.

While, as before stated, it has heretofore been common in this class of tickets to indicate the destination station by a notch or projection on the margin of the ticket, it has not 75 been common to indicate the particular class for which the ticket is sold in that manner. The names of the different classes have not heretofore been printed in the same columns which contained the station-names, but have 80 been printed on a different part of the ticket, and the class has been indicated by punching the ticket in or opposite the name of the class with the ordinary ticket-punch. So far as I am aware, I am the first in the art to produce 85 a ticket having the names of the different classes printed in the same columns as the station-names and having the particular class for which the ticket is issued indicated by a notch or projection on the margin of the passenger's portion of the ticket, and this without regard to the form of the notch or projection, so that this particular feature of my invention is not restricted to the division of the ticket upon a line which will form two 95 notches and an intermediate projection adjacent the name of the destination station, as heretofore described.

The blank for the round-trip ticket shown in Figs. 4 and 5 is composed of the stub portion A', the going portion B', and the return portion C'. The stub portion A' is or may be substantially the same as the stub portion A of the one-way ticket shown in Figs. 1 and 2. The portion C' adjacent to the stub forms the 100 return portion of the ticket, instead of the going portion, as in the one-way ticket. It corresponds substantially to the portion B of the one-way ticket, excepting that it preferably bears some wording to indicate that it 105 is a return ticket or coupon, and the station indicated by the notch or projection upon its margin becomes the starting station and the original starting station becomes the destination station, so that the ticket reads "From 110 station indicated on tongue between notches in margin to ——." This blank space will be 115 filled in in the same manner and at the same time as the original starting station upon the stub and going portions, as heretofore described. 120

The going portion B' of the ticket is preferably separated from the return portion C' by an indented or perforated line D' to facilitate the folding of the portion B' beneath the 125 portion C' and its subsequent separation from such portion during the going-passage. The going portion B' is provided with a duplicate series of station-names, the names in this instance being printed in reverse positions to those upon the stub and return portions of the ticket, but in the same order 130 from top to bottom of the ticket-blank. The portion C' is of such width that when it is

folded beneath the portion B' the names of the corresponding stations upon the two portions will exactly register with each other, so that if the folded ticket be placed beneath 5 the cutter and the portion B' severed from the stub portion in the manner heretofore described the right-hand margin of the portion C' will be torn off at the same time, and notches and projections formed upon the 10 edges of the ticket, the same as upon the left-hand margin of the portion B', as will be readily understood by reference to Fig. 5. The purpose of printing the station-names in reverse positions upon the going portion B' 15 of the ticket is to cause the name of the destination station to be indicated by notches and projections upon the left-hand margin of the ticket when it is issued, the same as upon the margin of the portion C', the ticket being 20 turned upside down from the position shown in Fig. 5 when it is taken in hand for use. Inasmuch as the destination stations upon all one-way tickets are indicated by notches and projections upon the left-hand margin of the 25 ticket it is desirable that they shall be so indicated upon each portion of a round-trip ticket; but it is evident that the names upon the portion B' of the round-trip ticket might be printed in the same order and position as 30 the names upon the stub and portion B', in which case the notches and projections indicating the station upon the going portion of the ticket would be on the right-hand margin of it instead of the left hand.

35 The going portion B' bears the words "From — to station indicated on tongue between notches in margin," the same as does the going portion of the one-way ticket.

From the foregoing description it will be 40 seen that by simply folding the portion B' of the round-trip ticket beneath the portion C', and then severing them from the stub portion A' in the same manner that the stub and ticket proper of the one-way ticket were separated, the going and return portions of the 45 round-trip ticket are simultaneously formed, and it is made as difficult to change the name of a station upon one portion of the ticket as it is upon the other.

50 I am aware that round-trip tickets having the stub and going and return portions arranged in the same relative positions as in my improved ticket, and in which the return portion of the ticket is separated from the 55 stub portion upon a line which forms a notch or projection in the margin of the return portion of the ticket opposite the original destination station, are old, but in none of such tickets with which I am familiar is the destination station upon the going portion of the ticket indicated by a notch or projection on the margin of the ticket. On the contrary, 60 in such tickets the going portion of the ticket is not provided with the names of the series of destination stations at all, and usually bears 65 simply some such words as "From — to station indicated in the margin," meaning the

station indicated in the margin of the return portion of the ticket, and the blank space being adapted to have the name of the original 70 starting station stamped or printed in it. The result is that in tickets of this class there is nothing whatever upon the going portion of the ticket, after it has been detached from the return portion, to indicate what the original destination station was. The going portion of the ticket, of itself, indicates nothing, and the destination station for which it was sold can only be determined by comparing the number of the ticket with the number of 80 the stub. It will be readily seen that this gives great opportunity for fraudulent manipulation of tickets of this class, which manipulation, however, is rendered impossible in my improved ticket by the provision of the 85 series of station-names upon the going portion of the ticket and the indication of the destination station by the notch or projection on the margin of such going portion in the same manner as upon the going portion of a one- 90 way ticket.

It will be understood from the above that the novelty of my improved round-trip ticket does not depend upon the indication of the station-names by the double notches and intermediate projections, though this feature of my invention is as valuable upon a round-trip ticket as upon a one-way ticket. This feature of my invention contemplates, broadly, the round-trip ticket having the names of 100 the series of stations printed upon both the going and return portions of the ticket and having the name of the original destination station indicated upon both the going and return portions by any sort of notches or projections upon the margin of such portions. 105

The going portion in the one-way ticket and the return portion in the round-trip ticket are provided adjacent one edge with a series of abbreviations of the names of the different 110 months of the year, a series of numbers indicating the different days of the month, and another series of numbers indicating the different years, adapted to be punched to indicate the date-limitation of the ticket, as is 115 usual in this and other classes of tickets. The going portion of the one-way ticket and both the going and return portions of the round-trip ticket are provided with special spaces at 120 G for the punching of the ticket to indicate 120 the checking of baggage, such spaces having printed upon them directions to punch for that purpose in those spaces and in those spaces only. The provision of these special spaces for the baggage-punch prevents obliteration of the date-limitation punches by means of a baggage-punch and the fraudulent manipulation of the date-limitation of the ticket by the punching of new date-numbers in it, as heretofore sometimes practiced. 125 130

Having thus fully described my invention, I claim—

1. A railroad-ticket having printed thereon a series of marks, indicating stations, and

having a projection at its edge opposite a pre-determined one of such marks, and indentations on either side of said projection, substantially as described.

5 2. A railway-ticket having printed thereon a series of marks indicating stations and having a projection at its edge opposite a pre-determined one of such marks, said projection being wholly within the line of the main 25 part of its edge, and indentations on either side of the said projection, substantially as described.

10 3. A railway-ticket having a series of station - names and class - characters printed thereon and having projections at its edge opposite a predetermined station-name and class-character, said name and character being printed partly on said projections, and 30 indentations on either side of said projections, substantially as described.

15 20

4. A round-trip railway-ticket comprising a going-coupon and a return-coupon having printed thereon a series of station-names, and having projections formed at their edges opposite predetermined station-names, and in- 25 indentations on either side of said projections, substantially as described.

5. A round-trip railway-ticket comprising a going-coupon and a return-coupon having corresponding station-names printed thereon 30 in reverse order, projections formed at the edges of said coupon portions opposite a predetermined station-name and within the line of the main part of the edges, and indentations on either side of said projections, sub- 35 stantially as described.
